United States Patent Office

Des. 204,827
Patented May 17, 1966

204,827

ATOMIZER

Louis D. Abramson, Milton, Mass.
(1259 Columbus Ave., Boston, Mass.)

Filed July 30, 1965, Ser. No. 86,362

Term of patent 14 years

(Cl. D58—9)

Fig. 1

Fig. 3

Fig. 2

Fig.4

Fig.5

FIG. 1 is a top plan view of an atomizer embodying my new design;

FIG. 2 is a front elevational view;

FIG. 3 is a side elevational view looking from the right of FIG. 2;

FIG. 4 is a rear elevational view; and

FIG. 5 is a side elevational view looking from the left of FIG. 2.

The dominant feature of my design resides in the portion shown in full lines.

I claim:

The ornamental design for an atomizer, as shown and described.
